UNITED STATES PATENT OFFICE.

NORMAN MARSHALL, OF BOSTON, MASSACHUSETTS.

ELECTRIC SWITCH.

SPECIFICATION forming part of Letters Patent No. 556,510, dated March 17, 1896.

Application filed December 14, 1895. Serial No. 572,112. (No model.)

To all whom it may concern:

Be it known that I, NORMAN MARSHALL, residing in Boston, county of Suffolk, and State of Massachusetts, have invented an Improvement in Electric Switches, of which the following description, in connection with the accompanying drawings, is a specification, like letters and figures on the drawings representing like parts.

10 This invention relates to electric switches or circuit-controllers of that class known as "quick-acting switches," and has for its object to provide a switch of the class referred to in which the movable contact member 15 may be thrown or moved in opposite directions with increased spring-power to obtain a quicker-acting, more efficient and durable switch.

In accordance with this invention the movable contact member is mounted on a suitable support to be moved in opposite directions, and has co-operating with it spring-actuated pawls or locking devices, one of which is in engagement with the movable contact member 25 when the latter is in engagement with the co-operating contact member, at which time the other of said pawls is disengaged from said movable contact member. The pawls referred to are disengaged from the movable contact member by a movable actuating device, and the said device in its movement acts upon a spring to store up energy, which is employed to throw or move the movable contact member of the switch when the latter is disengaged from its locking or holding pawl, the disengagement of the said pawl taking place at or about the time the spring is placed under maximum tension, so that when the movable contact member is released 40 by its holding-pawl it is placed under the control of the spring under maximum tension, and as a result the movable contact member is thrown or moved into or out from engagement with its co-operating contact member with increased force and speed, thereby reducing to a minimum the danger of arcing and insuring a more efficient operation of the switch.

These and other features of this invention 50 will be pointed out in the claims at the end of this specification.

Figure 1 represents in elevation one form

of switch embodying this invention; Fig. 2, a top or plan view of the switch shown in Fig. 1; Fig. 3, an elevation of the switch 55 shown in Fig. 1, with the actuating device in the position it occupies when the spring is placed under maximum tension; Fig. 4, a sectional detail on the line 4-4, Fig. 1, with parts in elevation; Figs. 5 and 6, similar views 6c to Figs. 1 and 3 of a modified form of switch; and Fig. 7, a sectional detail on the line 7-7, Fig. 5, to be referred to.

Referring to Figs. 1 to 4, inclusive, A represents one form of movable contact member 65 which is provided, as shown, with a contact-arm a , co-operating in the closed condition of the switch with a stationary contact arm or member a' , secured, as by screws a^2 , to a suitable support a^3 , which may be a plate or 70 wall of metal or other suitable material.

The movable contact member A, as herein shown, is loosely mounted on a stud or bolt a^5 , secured to the plate or support a^3 , it being shown as extended through a bushing 75 a^6 and fastened by the nut a^7 . The bolt or pin a^5 constitutes a pivot upon which the movable contact member A swings or turns, and the said contact member is adapted to be turned, as herein shown, by means of an 80 actuating-spring a^8 , coiled about the stud or pin a^5 and having its ends or arms 23 (see Fig. 1) extended down so as to cross each other and bear on opposite sides of a lug or projection a^9 on the movable contact member 85 A. The movable contact member A is provided on substantially diametrically-opposite sides with shoulders or projections a^{10} a^{12} , constituting teeth, with which co-operate teeth a^{13} a^{14} on pawls or locking devices a^{15} 90 a^{16} , the said pawls being pivotally secured at their lower ends, as at a^{18} a^{19} , to the plate a^3 .

In the construction shown in Fig. 1 the pawls a^{15} a^{16} are connected together at their upper ends by a spring a^{20} , and the said pawls 95 are provided with shoulders or arms a^{21} a^{22} , which are adapted to be engaged by curved or cam surfaces a^{23} a^{24} on an actuating device, herein shown as a pivoted plate or bar b . The pawls a^{15} a^{16} are adapted to be moved in 100 one direction by the cam-surfaces a^{23} a^{24} and to be moved in the opposite direction by the spring a^{20} , as will be described, and the said pawls are limited in their movements in op-

posite directions, as shown in Fig. 1, by means of fingers, lugs or projections $b^7 b^8$ on the said pawls extended into slots $b^3 b^4$ made in the plate a^3 . Each of the pawls $a^{15} a^{16}$ is preferably made in one piece, the pivot and the stop-finger being turned in one direction and the arm a^{21} turned in the opposite direction. The actuating device or plate b is loosely mounted upon the stud or bolt a^5 and is provided with a finger or projection b^4 , which normally stands in line with the finger or projection a^9 on the movable contact member A , and the arms $2 3$ on the actuating-spring a^8 extend into the path of movement of the finger b^4 , so that when the actuating device or plate b is turned on its pivot in one direction one arm of the said spring will be moved or carried away from its normal position shown in Fig. 1 into the position shown in Fig. 3, thereby placing the actuating-spring a^8 under tension until the tooth a^{13} on the pawl a^{15} has been disengaged from the tooth a^{10} on the movable contact member A , and when disengaged the actuating-spring a^8 , through its arm 2, acting on the finger or projection a^9 , will turn the contact member A on its stud or pivot a^5 in the direction indicated by arrow 20, Fig. 3, until the contact-arm A meets a suitable stop. (Shown as a pin or stud b^7 .) The movement of the contact member A in the direction indicated by the arrow 20 withdraws the contact-arm a from engagement with the co-operating contact member a' , thereby opening the switch. By reference to Fig. 3 it will be seen that the actuating-spring a^8 for the movable contact member A is placed under maximum tension at or about the time the holding-pawl a^{15} is disengaged from the tooth a^{10} on the contact member A , so that when the pawl a^{15} is disengaged the contact member A is moved with a maximum force, thereby insuring quick withdrawal of the contact-arm a from the stationary contact-arm a' .

In the open position of the switch shown in Figs. 1 to 4, inclusive, the contact-arm a is disengaged from the stationary arm a' , and the tooth a^{14} of the holding-pawl a^{16} is in engagement with the tooth or projection a^{12} on the contact member A , and the actuating bar or plate b occupies substantially the position shown in Fig. 3.

In Fig. 3 the contact member A is represented in its normal position, while the plate of bar b is represented in substantially the reverse position from that shown in Fig. 1, in order that the effect of the maximum tension of the spring may be more clearly understood. When the contact member A of the switch is in its open position, which in this case would be with the arm a disengaged from the stationary arm a' , and the lug or projection a^9 substantially in line with the lug or projection b^4 , (shown in Fig. 3,) it may be moved back into its closed position by turning the actuating bar or plate b in a direction opposite to that indicated by the arrow 20, so that in this case the arm 2 of the actuating-spring

a^8 will be carried by the finger b^4 in the direction opposite to that indicated by the arrow 20, while the tooth a^{14} of the holding-pawl remains in engagement with the tooth or projection a^{12} on the contact member A , which movement places the actuating-spring under maximum tension at the time the pawl a^{16} is disengaged from the tooth a^{12} , so that the arm 3 of the actuating-spring a^8 in this case acts upon the finger or projection a^9 and throws the contact-arm a of the movable member A into engagement with its co-operating member a' . This reciprocating motion of the actuating plate or bar b may be effected, as represented in Figs. 1 to 3, inclusive, by means of push buttons or rods $b^{12} b^{13}$ pivotally connected to arms $b^{14} b^{15}$ extended from the bar or plate b .

For some classes of work I may prefer to embody my invention in the construction represented in Figs. 1 to 4; but I do not desire to limit my invention in this respect, as the said invention may be embodied in other forms—as, for instance, that shown in Figs. 5 to 7, inclusive. Referring to Figs. 5 to 7, inclusive, A' represents the movable contact member provided with a contact-arm c , which co-operates with a stationary contact member c' fastened to a suitable support, represented as a block c^2 of insulation, fastened to the supporting-wall or back plate c^3 . The contact member A' is loosely mounted on a pivot c^4 , (shown as a screw or stud,) which is secured to the plate or support c^3 , and on substantially diametrically opposite sides the contact member A' is provided with teeth or projections $c^5 c^6$, which may be formed by upsetting a portion of the plate from which the movable contact member is made. The movable contact member A' is also provided, as shown in Figs. 5 to 7, inclusive, with lugs, projections or fingers $c^8 c^9$, to which are secured the opposite ends of springs $c^{10} c^{11}$, which, as herein shown, encircle guide-rods $c^{12} c^{13}$ pivotally connected, as at c^{14} , to the arm c^{15} of the actuating device c^{16} , the outer ends of the guide-rods $c^{12} c^{13}$ being forked or slotted to embrace or straddle the studs or fingers $c^8 c^9$. The springs $c^{10} c^{11}$ are fastened at what may be termed their "inner ends" to the pivot or screw c^{14} .

The movable contact member A' is thrown or moved in one direction on its pivot by the spring c^{10} and in the other direction by the spring c^{11} , and the said member has co-operating with it spring-actuated pawls or locking devices $c^{20} c^{21}$, which are shown as projections on blocks $c^{22} c^{23}$, movable in openings c^3 extended through the plate c^3 and secured to springs $c^{25} c^{26}$, located behind and fastened to the plate c^3 , as by screws c^{27} . The blocks or plates $c^{22} c^{23}$ normally project through the plate, so that the lower portions of their front faces may be engaged by the upper ends 51 of the actuating device, plate, or bar c^{16} . The blocks $c^{22} c^{23}$ may, and preferably will, be made so as to form inclined surfaces 10 12,

with which co-operate the ends 50 51 of the actuating plate or bar c^{16} , so that when the said actuating bar or plate is turned on the pivot c^4 in one direction—as, for instance, in the direction indicated by arrow 40—one end, as 50, of the plate or bar will force the block c^{22} back through the opening in the plate c^3 , until the pawl or projection c^{20} is withdrawn from engagement with the tooth or projection c^5 on the contact member A' , and when so disengaged the spring c^{11} , which at such time is under maximum tension, turns or throws the contact member A' on its pivot and withdraws the contact-arm c from engagement with the contact-arm c' . The movement of the contact member A on its pivot when released from its holding-pawl c^{20} is augmented by the spring c^{10} , which is under compression when the contact member A' is in the position shown in Fig. 5.

The movements of the actuating bar or plate c^{16} just described may be effected by turning the handle c^{40} in the direction of arrow 60, Fig. 5, which movement of the handle turns the plate or bar c^{16} , so that the opposite end 51, now in engagement with the pawl or projection c^{21} , will travel down the inclined face of the block c^{23} and permit the spring c^{26} to force the said block into position in front of the plate c^3 to be engaged by the tooth or projection c^6 on the contact member A' , when the latter has been carried by the said pawl or projection—that is, when it is in its open position. When the contact member A' is in its open position, which may be supposed to be with its arm c in engagement with the stoppin c^{45} , the spring c^{12} is at such time ready to be placed under tension when the handle c^{40} is moved in the direction opposite to that indicated by the arrow 60. When the handle c^{40} is moved in the direction opposite to that indicated by the arrow 60, the block c^{23} is pushed back against the action of its spring c^{26} until the pawl or projection c^{21} is withdrawn from engagement with the tooth or projection c^6 , at which time the spring c^{10} is under maximum tension and turns the contact member A' on its pivot and brings the contact-arm c into engagement with the stationary contact-arm c' . In the constructions herein shown and described it will be noticed that the movable contact member is turned or carried by its spring in the same direction as the actuating device.

I have herein shown my invention as embodied in a single-pole switch; but I do not desire to limit my invention in this respect, as it may be embodied in multipolar switches.

The parts of the switch herein shown will in practice be inclosed in a suitable casing or mounted upon a suitable support of insulating material.

The form of switch shown in Figs. 5 to 7 is especially designed for use in circuits carrying heavy currents—as, for instance, in arc lights and power-circuits—while that shown in Figs. 1 to 4 is designed for use in circuits

carrying light currents, such as battery-currents.

I claim—

1. In a quick-acting switch, the combination of the following instrumentalities, viz.—a pivoted contact member provided with a lug or projection, a pivoted actuating bar or plate provided with a lug or projection normally in line with the lug or projection on the contact member, a spring encircling the pivot for the said contact member and actuating bar or plate and provided with arms engaging the opposite sides of the said lugs to normally hold the said lugs in line with each other, each of the said arms being placed under tension by the movement of the lug on the actuating-bar away from or out of line with the lug on the contact member, and means to lock the said contact member in its opened and closed positions, substantially as and for the purpose specified.

2. In a quick-acting switch, the combination of the following instrumentalities, viz.—a pivoted contact member movable in opposite directions and provided with teeth $a^{10} a^{12}$, holding-pawls having teeth co-operating with the teeth $a^{10} a^{12}$, and provided with arms $a^{21} a^{22}$, a spring to normally move said pawls toward the contact member, a lug or projection on said contact member, a pivoted actuating bar or plate having cam-surfaces to engage the arms $a^{21} a^{22}$ of the said pawls, a lug or projection on the actuating plate or bar normally in line with the lug or projection on the contact member, a spring encircling the pivot of the said contact member and its actuating bar or plate and having crossing arms which engage the lugs on the said contact member and its actuating bar or plate, whereby movement of the actuating bar or plate in one direction places the said spring under tension to move the said contact member in the same direction, when released from its holding-pawl, substantially as described.

3. In a quick-acting switch, the combination of the following instrumentalities, viz.—a pivoted contact member movable in opposite directions and provided with teeth, holding-pawls co-operating with said teeth, a pivoted actuating plate or bar movable in opposite directions and adapted to disengage the holding-pawls from the movable contact member, a spring placed under tension by the movement of the actuating plate or bar and acting on the movable contact member to turn the same on its pivot in the same direction as that in which the actuating-bar is moved, substantially as described.

4. In a quick-acting switch, the combination of the following instrumentalities, viz.—a pivoted contact member provided with teeth and movable in opposite directions, spring-actuated holding-pawls co-operating with said teeth, a pivoted actuating plate or bar movable in opposite directions and adapted to engage said pawls to withdraw them from engagement with the contact member, and a

spring operatively connected to the said contact member and to the actuating bar or plate to be placed under maximum tension at or about the time the holding-pawl is disengaged 5 from the contact member, to act on the said contact member and move it in the same direction as the actuating plate or bar, substantially as described.

In testimony whereof I have signed my name to this specification in the presence of 10 two subscribing witnesses.

NORMAN MARSHALL.
